posted: Nov. 24, 2013 TheFirearmBlog [visited: Sep. 20, 2021]

FIG. 1 is a top right perspective view of a firearm tool, according to the present invention;

FIG. 2 is a top left perspective view of the firearm tool of FIG. 1;

FIG. 3 is a right side elevation view of the firearm tool of FIG. 1;

FIG. 4 is a left side elevation view of the firearm tool of FIG. 1;

FIG. 5 is a front elevation view of the firearm tool of FIG. 1;

FIG. 6 is a rear elevation view of the firearm tool of FIG. 1;

FIG. 7 is a top plan view of the firearm tool of FIG. 1;

FIG. 8 is a bottom plan view of the firearm tool of FIG. 1;

FIG. 9 is a bottom right perspective view of the firearm tool of FIG. 1;

FIG. 10 is a bottom left perspective view of the firearm tool of FIG. 1;

FIG. 11 is a top left cross-sectional perspective view of the firearm tool taken along lines 11-11 of FIG. 2; and,

FIG. 12 is a top right cross-sectional perspective view of the firearm tool taken along lines 12-12 of FIG. 1.

The broken lines shown in FIGS. 1 and 2 annotate cross-sectional views of the firearm tool and form no part of the claimed design.

1 Claim, 5 Drawing Sheets
